LEATHER DYEING MACHINE

Charles Herbert Vail, Johnstown, N. Y.

Application March 26, 1934, Serial No. 717,515

6 Claims. (Cl. 8—19)

This invention relates to an improved machine for dyeing leather, and the primary object of the present invention is to provide a machine of this kind by means of which the dye may be efficiently supplied to and uniformly spread over the surface of the leather, as well as thoroughly brushed into the leather.

A more specific object of the present invention is to provide a machine of the above kind including a revolving hollow cylindrical brush provided with alternate rows of perforations and bristles, a leather carrying table movable into engagement with the under side of and shiftable relative to said brush, and means to supply the dye to the interior of the brush, whereby the dye may flow through the perforations of the brush body onto the surface of the leather for being subsequently spread uniformly over the surface of and thoroughly brushed into the leather by the rows of bristles that alternate with the rows of perforations of the brush.

A further object of the present invention is to provide the brush with flexible striker strips that normally close the rows of perforations in the cylindrical body of the brush and that are arranged to be flexed by contact with the leather so as to uncover the rows of perforations normally covered thereby, whereby the supply of the dye to the surface of the leather is properly restricted and controlled to avoid a great excess flow of dye onto the leather and to allow the dye to flow onto the leather through only one row of perforations at a time at the bottom of the brush and immediately prior to engagement of the adjacent row of bristles with the surface of the leather so that the dye will be uniformly spread over the surface and thoroughly rubbed into the leather.

Still another object of the present invention is to provide means for heating and maintaining the leather carrying table at a uniform temperature whereby the leather may be brought to a proper temperature for facilitating application of the dye to and penetration of the dye in the leather.

Still another object of the present invention is to provide a machine of the above kind in which the leather carrying table is shiftable to and from a position beneath the dyeing roller, means for elevating the table when in position beneath the brush so as to bring the leather on the table in engagement with the latter, and power-operated means automatically rendered operative when the table is raised for shifting said table relative to the brush so as to effect application of and

spreading of the dye over the entire portion of the surface of the leather presented to the brush at each operation.

The invention further contemplates a table shiftable within certain limits relative to the brush and rotatable about a vertical axis so that substantially one-half of the leather may be dyed at each operation.

Other objects and features of the present invention will become apparent from the following description when considered in connection with the accompanying drawings, in which:

Figure 1 is a top plan view, partly broken away and in section, of a leather dyeing machine embodying the present invention.

Figure 2 is a front elevational view thereof, partly broken away and in section.

Figure 3 is a vertical longitudinal section on line 3—3 of Figure 2.

Figure 4 is a central transverse sectional view of the leather carrying table and its supporting carriage; and

Figure 5 is an enlarged transverse section of the dyeing brush.

Referring more in detail to the drawings, the machine illustrated includes a suitable frame 5 at the top of which is arranged a revolving hollow cylindrical brush 6 journaled in fixed bearings 7. As shown clearly in Figures 1, 3 and 5, the brush 6 includes a hollow cylindrical body 8 provided with alternate longitudinal rows of perforations 9 and bristles 10 which may run parallel with the axis of the brush but are shown by way of example as spirally arranged. Attached to the surface of the cylindrical body 8 of the brush are flexible striker strips 11, preferably made of yieldable material such as rubber or rubber composition, and each of which is arranged to normally cover an entire row of perforations 9. It is to be understood that a striker strip 11 is provided for each row of perforations, and said strips are provided with outstanding ribs or flanges whose outer edges are preferably substantially flush with the outer ends of the bristles 10. By reason of this arrangement, when the leather 12 to be dyed is brought into engagement with the under side of the brush and the latter is rotated, the lowermost striker strip will be flexed so as to uncover the row of perforations 9 normally covered thereby, thus permitting the dye to flow from the interior of the brush body 8 outwardly onto the surface of the leather. As the brush continues to rotate, the adjacent row of bristles engages the surface of the leather and uniformly spreads the dye thus supplied to

the surface of the latter. This alternate supply of dye and spreading of the same over the surface of the leather is constantly repeated as the successive striker strips and rows of bristles move into engagement with the surface of the leather, the dye being thoroughly brushed into the leather as well as being uniformly spread over the surface thereof by the successive rows of bristles 10. A suitable hood 13 is mounted over the upper portion of the brush 6 and provided with an outlet pipe 14 adapted to be connected with the suction side of a conventional blower, not shown, so that fumes from the dye may be drawn off and suitably disposed of during the dyeing operation.

A tilttable guide frame 15 is mounted in the main frame 5 of the machine below the brush 6, so as to rock vertically upon a horizontal axis intermediate its ends, such axis being provided by lateral trunnions 16 rigid with and projecting from the sides of the guide frame 15 and journaled in the sides of the main frame 5 as shown clearly in Figures 2 and 3. Guided in the frame 15 for movement longitudinally of the machine is a suitable roller carriage 17, and centrally journaled in this carriage is a depending central stub shaft 18 rigid with and depending from the center of a leather carrying table 19, whereby said table is mounted on the carriage 17 for rotation about a horizontal axis. The guide frame 15 is so proportioned and arranged that the carriage 17 may be shifted to either bring the table 19 to a forward position entirely away from beneath the brush 6 as shown in Figure 3 or to a rearward position with the axis of rotation of said table 19 slightly rearwardly of a vertical plane intersecting the axis of brush 6. The proper limiting of the shifting movement of carriage 17 may be accomplished by suitable stops such as end members of the frame 15, as shown. It will also be noted that the guide frame 15 is adapted to be slightly tilted to a rearwardly inclined position as shown in Figure 3, so that after the leather is placed on the table 19, the latter may be freely shifted to a rearward position beneath the brush without permitting engagement of the latter with the leather. The guide frame 15 may then be tilted in an opposite direction so as to raise the rear end portion of guide frame 15 and thereby bring the leather on the table 19 into engagement with the under side of the brush 6. It will be understood that the leather may be placed on the table 19 to extend an equal distance forwardly and rearwardly of its vertical axis of rotation defined by shaft 18, and thus when the table is fed forwardly and the brush is rotated, substantially one-half of the leather will be dyed or coated at each operation. By rotating the table 180°, and repeating the rearward positioning and forward feeding movement of the table, the entire surface of the leather may be dyed, each dyeing operation being in full view of the operator. A downwardly spring-pressed roller 20 is journaled in the main machine frame 5 directly in front of the brush 6 and above the table 19 so that when the guide frame 15 is tilted to engage the leather with the brush 6, the forward portion of the leather on the table 19 will be firmly gripped between said table and the roller 20 so as to be held flatly on the table and to prevent rotation of brush 6 from displacing the leather rearwardly relative to the table as the latter is fed forwardly during the dyeing operation, the brush 6 being

rotated in a counterclockwise direction as indicated by the arrow in Figure 3.

Means is provided to permit the carriage 17 and table 19 to freely gravitate to the rearward position relative to guide frame 15, and to automatically feed the carriage and table forwardly when the guide frame 15 is tilted to bring the leather into engagement with brush 6 while the table is in the rearward position. For this purpose, a power driven pinion 21 is journaled at the front of the main frame 5, and a longitudinal rack bar 22 is fixed to the under side of carriage 17 in position to engage the pinion 21 when the guide frame 15 is tilted to raise its rear end portion and to cause the aforesaid engagement of the leather on table 19 with the brush 6. Obviously, as soon as the leather is engaged with the brush 6, the rack bar 22 is engaged with pinion 21 and the latter cooperates with said rack bar for feeding the carriage and table to the forward position. When the carriage and table reach the forward position of Figure 3, the rack bar 22 will ride forwardly out of engagement with pinion 21, whereupon the leather may be removed from the table and a new piece of leather placed thereon to be dyed. The guide frame 15 is then tilted so as that its lower end portion is lowered and its forward end portion is raised, thereby positioning the rack bar 22 out of the path of pinion 21 and permitting free gravitation of the carriage 17 and table 19 to the rear operative position.

Arranged beneath the rear portion of guide frame 15 is an open top tank 23 into which excess dye may readily flow from the leather on the table 19 during the dyeing operation. This tank 23 has a bottom outlet connected with the intake of a pump 24 whose outlet is connected by a pipe line 25 with the interior of brush 6, the line 25 extending through a hollow shaft on one end of brush 6 so as to not interfere with rotation of the latter. In this way the used dye may be returned to the brush for re-use. Any suitable means may be provided for driving the brush 6, the pinion 21 and the pump 24. As shown, this is accomplished by a belt gearing associated with these elements and a driving motor 26 mounted on one side of the machine, such gearing including a single endless transmission belt 27.

The table 19 is provided with suitable heating means and suitable means for controlling such heating means whereby the table may be maintained at a uniform desired temperature so that the leather placed on said table may be brought to the desired temperature to facilitate application of the dye to and penetration of the dye in the leather. As an example of one kind of suitable heating means, the table 19 may be of hollow construction and supplied with water by means of a water supply pipe 28 extending from a suitable source and projecting into the hollow stub shaft 18 so that the latter is freely revoluble relative to said pipe 28. The water supplied may be heated at its source, or the table 19 may be equipped with one or more electrical emersion heaters 29 controlled by a thermostat 30 in electrical connection with a thermo-couple 31 subjected to the temperature of the water within the table 19. The water supply pipe 28 may have a branch 32 to permit escape of excess water due to expansion, the escape being controlled either by a safety pressure relief valve 33 or by an arrangement making use of the ordinary overflow principle.

It is desirable to permit treatment of the

leather with a striking acid or water while on the table 19 with the latter in its forward inoperative position of Figure 3, and in order to catch the excess acid or water flowing from the leather and table when the latter is in such forward position, an open top tank 34 is suitably mounted below the guide frame 15 at the front of the machine. In this way the striking acid or water is caught by the tank 34 and prevented from flowing into the rear tank 23 containing the dyeing liquid.

In operation, the leather is placed on table 19 with the parts positioned as shown in Figure 3, whereupon the table is released to gravitate rearwardly relative to the guide frame 15 to a position beneath the brush 6 so that slightly more than one-half of the leather will be positioned rearwardly of a vertical plane intersecting the axis of said brush 6. The guide frame 15 is then tilted to raise its rear portion and bring the leather on table 19 into engagement with the under side of brush 6. This simultaneously causes engagement of rack bar 22 with pinion 21, thereby causing the carriage 17 and table 19 to be fed forwardly. The rotation of the brush and the forward feeding movement of the table accomplishes dyeing of slightly more than one-half of the leather in the manner previously described, and when the table reaches its forward position it may be rotated 180° and then the dyeing operation just described may be repeated to complete dyeing of the entire piece of leather.

It will be seen that I have provided a comparatively simple and efficient machine for carrying out the stated objects of the invention and one which will require a minimum amount of attention and manual labor on the part of the attendant or operator. Minor changes in the details of construction illustrated and described are contemplated within the spirit and scope of the invention as claimed.

What I claim as new is:

1. In a leather dyeing machine, a revolving hollow cylindrical brush for applying the dye to the surface of the leather, said brush being provided with alternating longitudinal rows of perforations and bristles, and means to supply the dye to the interior of said brush and means normally closing said rows of perforations and provided with projecting parts engageable with the leather to cause said means to successively uncover the perforations normally closed thereby.

2. In a leather dyeing machine, a revolving hollow cylindrical brush for applying the dye to the surface of the leather, said brush being provided with alternating rows of perforations and bristles, means to supply the dye to the interior of said brush, and flexible striker strips normally closing said rows of perforations and provided with projecting portions engageable with the leather to successively flex said striker strips for uncovering the perforations normally closed thereby.

3. In a machine for dying leather, a revolving cylindrical fountain brush for applying the dye to and spreading the same over the surface of the leather, a leather carrying table movable substantially horizontally to and from a position beneath said brush, said table further being movable upwardly for bringing the leather into engagement with said brush, means rendered operable by

upward movement of the table for feeding said table from a position beneath the brush to a position forwardly of the latter, said table being mounted for rotation about a vertical axis, and means for limiting movement of the table in the direction toward and beneath the brush whereby substantially one-half of the leather may be dyed at a time and both halves of the leather may be dyed by successive operations with the table rotated 180° for the second operation.

4. In a machine for dyeing leather, a guide frame tiltable intermediate its ends about a transverse horizontal axis, a carriage longitudinally movable in said frame, a table mounted on said carriage for rotation about a vertical axis, a revolving cylindrical fountain brush for supplying the dye to and spreading it over the surface of the leather placed on said table, the table and brush being relatively arranged so that when the guide frame is tilted in one direction the table may be raised to bring the leather into engagement with the brush, and means automatically rendered operable upon tilting of the guide frame in the last-named direction for feeding said carriage and table relative to and from beneath the brush.

5. In a machine for dyeing leather, a guide frame tiltable intermediate its ends about a transverse horizontal axis, a carriage longitudinally movable in said frame, a table mounted on said carriage for rotation about a vertical axis, a revolving cylindrical fountain brush for supplying the dye to and spreading it over the surface of the leather placed on said table, the table and brush being relatively arranged so that when the guide frame is tilted in one direction the table may be raised to bring the leather into engagement with the brush, means automatically rendered operable upon tilting of the guide frame in the last-named direction for feeding said carriage and table relative to and from beneath the brush, and a spring pressed roller arranged to cooperate with the table and grip the leather when the latter is brought into engagement with the brush by the aforesaid tilting of the guide frame to hold the leather flat on the table and prevent displacement of the same relative to the table by the brush as the table is fed relative to the latter.

6. In a machine for dyeing leather, a guide frame tiltable intermediate its ends about a transverse horizontal axis, a carriage longitudinally movable in said frame, a table mounted on said carriage for rotation about a vertical axis, a revolving cylindrical fountain brush for supplying the dye to and spreading it over the surface of the leather placed on said table, the table and brush being relatively arranged so that when the guide frame is tilted in one direction the table may be raised to bring the leather into engagement with the brush, means automatically rendered operable upon tilting of the guide frame in the last-named direction for feeding said carriage and table relative to and from beneath the brush, an open tank beneath the inner end of the guide frame to receive excess dye drained from the leather, and power-operated means for continuously supplying the dye from said tank to said brush.

CHARLES HERBERT VAIL.
